COMPOSITE STORE COUNTER AND STORAGE CABINET OR THE LIKE

Louis A. Banks, Glenview, Ill., assignor to The Waddell
Company, Greenfield, Ohio, a corporation of Ohio

Application November 14, 1957, Serial No. 48,447

Term of patent 14 years

(Cl. D80—11)

FIG. 1.

FIG. 2.

FIG. 3.

Figure 1 is a top plan view of a composite store counter and storage cabinet or the like, showing my new design; Figure 2 is a front elevational view thereof;

The rear of the article is substantially the same as the front shown in Figures 2 and 4, but has only a single panel.

I claim:

The ornamental design for a composite store counter and storage cabinet or the like, as shown and described.
